Primary Examiner — Richard Edgar*Assistant Examiner* — Liv C Anderson*(74) Attorney, Agent, or Firm* — JCIPRNET(57) **CLAIM**

The ornamental design for a lamp as shown and described.

DESCRIPTION

FIG. 1 is a top, front, right perspective view of a lamp showing our new design;

FIG. 2 is a top, rear, left perspective view thereof;

FIG. 3 is a top, front, left perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines shown in the figures and the lower opacity areas within the broken lines, is for the purpose of illustrating portions of the lamp that form no part of the claimed design.

1 Claim, 9 Drawing Sheets(56)
